PORTABLE ELECTRIC LIGHTING FIXTURE

David J. Biller, St. Louis, Mo., assignor to Day-Brite Lighting, Inc., St. Louis, Mo., a corporation of Missouri

Application January 14, 1943, Serial No. 472,323

8 Claims. (Cl. 240—11.4)

This invention relates to electric lighting fixtures, particularly portable fluorescent lighting fixtures. The invention has for its principal objects to provide a strong and durable, simple and efficient portable fluorescent lighting fixture that can be suspended in an upright position or supported on and drawn or slid in a horizontal position without rolling; that will permit ready insertion and removal of the lamps and protect them from injury; that will direct the light in the desired direction and protect the eyes from the glare of the light; and that will provide a concealed mounting for the wiring and auxiliary devices of the lamp circuit. The invention consists in the portable electric lighting fixture and in the parts and combinations and arrangements of parts hereinafter described and claimed.

In the accompanying drawings, which form part of this specification and wherein like symbols refer to like parts wherever they occur,

Fig. 1 is a perspective view of a portable fluorescent lighting fixture embodying my invention, the fixture being shown disposed horizontally and supported on the longitudinal runners thereof,

Fig. 2 is a side elevational view, showing the fixture suspended in an upright position by the hook at the upper end thereof,

Fig. 3 is an enlarged end elevational view of the hook end of the fixture,

Fig. 4 is a similar view of the opposite end of the fixture,

Fig. 5 is a part side elevational and part longitudinal sectional view of the fixture,

Fig. 6 is a cross-sectional view on the line 6—6 in Fig. 5,

Fig. 7 is a cross-sectional view on the line 7—7 in Fig. 1,

Fig. 8 is a fragmentary longitudinal section on the line 8—8 in Fig. 6,

Fig. 9 is a side view of the combination reflector and eye shade of the fixture,

Fig. 10 is a perspective view of a modified form of fixture, the bail member of the fixture being shown turned under one end thereof to support the fixture in reclining position,

Fig. 11 is a side elevational view, showing the modified form of fixture suspended in upright position by the bail at the upper end thereof; and

Fig. 12 is an enlarged elevational view of the bail end of the fixture, with the bail member in the position shown in Fig. 11.

The portable electric lighting fixture shown in Figs. 1 to 9, inclusive, comprises a cylindrical cage

5 A, cup-shaped end caps B for said cage, and runners C for rotatably supporting said end caps. The cylindrical cage A comprises a tubular body including an openwork portion of woven wire screen 1, which forms the major part of the tube, and an imperforate plate 2, which forms the remaining portion thereof. The ends of the cage A are closed by circular disks 3 having peripheral flanges 4 that fit within and are secured by screws 5 to the opposed open ends of the cup-shaped end members or caps B and constitute closures therefor. The longitudinal wires of the screen 1 seat against the inner faces of the peripheral flanges 4 of the closure disks 3 and are welded thereto; and the spaced longitudinal edges of said screen have trim members 6 crimped thereover and welded to said closure disks.

20 A rigid tube or pipe 7 extends longitudinally of the cylindrical cage A from end to end thereof adjacent to one of the edge trim strips 6 of the screen 1 and communicates through openings in the end closure disks 3 with the chambers 8 closed thereby in the cup-shaped end members or caps B. The tube 7, like the screen 1, is welded to the end closures 3, whereby said tube, screen and end closures are permanently connected together to form a unitary cage structure.

25 The spaced apart edge trim strips 6 of the screen 1 of the cylindrical cage A define the longitudinal side edges of an opening 9 therein through which access is had to the interior thereof. The longitudinal access opening 9 in the cage A is normally covered by the imperforate plate 2, which is detachably secured to said cage by means of spring clips 10 that are welded or otherwise secured to the longitudinal edges of said plate and are adapted to snap over the edge trim strips 6. Located inside the cage A are one or more longitudinally disposed tubular lamps 11 that are supported at their ends in suitable lampholders 12 that are secured by screws 13 to the concealed or inner faces of the end closure disks 3 with their lamp socket portions 12a disposed in openings 14 provided therefor in said disks.

30 The lamp circuit for the above fluorescent lighting fixture includes ballasts or current limiting devices 15, which are enclosed within the chambers 8 and are secured by screws 16 to the concealed faces of the end closure disk 3, a combination control and starter switch 17 mounted in one of said chambers and having an operating knob 17a located exteriorly thereof, a plug-in cord 18 extending into said chamber, and wires (not shown) running through the conduit 7 to said

ballasts, said switch and the lampholders 12 in said chambers.

The runners C extend longitudinally of the fixture along one side thereof and have laterally curved converging end portions 18 that terminate in registering eyes 20 adapted to receive screws 21 for securing said eyes to the outer ends of the respective cup-shaped end caps B of the fixture. The screws 21 extend through the registering eyes or loops 20 of the runners C and are threaded into suitable fittings 22 that are welded or otherwise permanently secured in central openings provided therefor in the outer ends of the respective end caps B, whereby the cage A, end caps and the parts enclosed therein may be rotated as a unit relative to said runners about the axes of said screws. The fixture is provided with a hook member 23 that is connected to one end thereof for swiveling movement relative thereto by means of the screw 21 at that end of said fixture.

By the arrangement described, the fixture may be supported on the runners C thereof and drawn or slid in horizontal position, the runners preventing the fixture from rolling sidewise. The fixture may also be suspended in an upright position by means of the swiveled hook 23 at one end thereof. The closure plate 2 serves as a reflector and as a shade; and in both horizontal and upright positions of the fixture, the entire body portion thereof may be rotated about the screws 21 as a center so as to locate the combined cover plate, reflector and eye shade 2 in a position that will reflect the light in the desired direction and protect the eyes from the glare of the light. The wires of the lamp circuit are concealed within the end chambers 8 and in the wiring conduit 1 extending theretwix; and the ballasts 15, control and starter switch 17 and other accessories are entirely concealed within said chambers. The combination cover, reflector and eye shade 2 may be readily detached from the fixture to permit removal and replacement of the lamps 11 and the ballasts 15; and lampholders 12 are supported entirely by the closure disks 8 for inspection, repair or replacement merely by endwise separation of the cup members B from said closure disks.

The modified form of the fixture shown in Figs. 10, 11 and 12 is similar to the fixture hereinbefore described except that in the modified fixture construction the runners C and hook 23 are dispensed with and a hinged and swiveled bail member 24 is substituted therefor. The bail member 24 has a hinge connection 25 with a plate 26 that is pivotally secured by means of a screw 27 to the outer end of one of the end caps B of the fixture, whereby said bail member may be swung beneath one end of the fixture to support the same in reclining position or may be swung outwardly in substantially endwise alignment with the fixture for suspending the same in an upright position. As shown in Fig. 12, the bail member 24 has a wide or flared intermediate portion 24a, which acts as a chock or clog to prevent rolling of the fixture, and a rebent free end portion 24b, which in the position shown in Fig. 11 constitutes a suspension hook for the fixture.

Obviously, the hereinbefore described portable electric lighting fixture admits of considerable modification without departing from the invention. Therefore, I do not wish to be limited to the precise construction shown and described.

What I claim is:

1. A portable electric lighting fixture comprising a light transmitting tube having an access

opening in the side thereof, a cover member for said opening, closures for the ends of said tube, caps secured to said end closures and cooperating therewith to form chambers at the ends of said tube, a wiring conduit extending from end closure to end closure inside said tube and opening into said chambers, lampholders located in said chambers and sustained by said end closures and having lamp socket portions opening through said end closures into said tube, ballast members located in said chambers and sustained by said end closures, and runners extending longitudinally of said fixture and supporting said end caps for rotation about the longitudinal axis of said lamp enclosing tube.

2. A portable electric lighting fixture comprising a cylindrical lamp enclosing cage including a wire screen forming a portion of said cage and a removable cover, shade and reflector member forming the remaining portion thereof, closures for the ends of said cage, cup-shaped caps separably secured to said end closures and cooperating therewith to form chambers at the ends of said cage, a wiring conduit extending from end closure to end closure inside said cage and opening into said chambers, lampholders located in said chambers and sustained by said end closures and having lamp socket portions opening into said cage, ballast members located in said chambers and sustained by said end closures, and runners extending longitudinally of said fixture and supporting said end caps for rotation about the longitudinal axis of said lamp enclosing tube.

3. A portable electric lighting fixture comprising a lamp enclosing cage including a cylindrical light transmitting tube having an access opening in the side thereof through which a lamp may be inserted in and removed from said tube, a cover member for said opening, closures for the ends of said tube having peripheral flanges secured thereto, caps separably secured to the peripheral flanges of said end closures and cooperating therewith to form chambers at the ends of said cage, lampholders located in said chambers and sustained entirely by said end closures and having lamp socket portions opening through said end closures into said cage, runners extending longitudinally of said fixture and supporting said end caps for rotation about the longitudinal axis of said lamp enclosing tube, and a supporting hook secured to one of said end caps.

4. A portable electric lighting fixture comprising a lamp enclosing cage including a wire screen tube having a longitudinal access opening in the side thereof through which a tubular lamp may be inserted and removed sidewise, trim strips secured to said screen and defining the edges of said opening, closures for the ends of said tube, a cover member for said opening, cup-shaped caps secured to said end closures and cooperating therewith to form chambers at the ends of said cage, and lampholders located in said chambers and sustained by said end closures and having lamp socket portions opening into said cage and adapted to support said lamp therein, said cover member constituting a reflector and eye shade and having spring fastener members adapted for snap engagement with said trim strips.

5. A portable electric lighting fixture comprising a lamp enclosing cage including a wire screen tube having a longitudinal access opening in the side thereof through which a tubular lamp may be inserted and removed sidewise, trim strips

secured to said screen and defining the edges of said opening, closures for the ends of said tube, a cover member for said opening, cup-shaped caps secured to said end closures and cooperating therewith to form chambers at the ends of said cage, and lampholders located in said chambers and sustained by said end closures and having lamp socket portions opening into said cage and adapted to support said lamp therein, said cover member constituting a reflector and eye shade and having spring fastener members adapted for snap engagement with said trim strips, and a bail member connected to one of said caps, said bail member being adapted and arranged to swing alongside of said cap to support the fixture in a reclining position and to prevent the same from rolling sidewise in such position.

6. A portable electric lighting fixture comprising a lamp enclosing cage including a wire screen tube having a longitudinal access opening in the side thereof through which a tubular lamp may be inserted and removed sidewise, trim strips secured to said screen and defining the edges of said opening, closures for the ends of said tube, a cover member for said opening, cup-shaped caps secured to said end closures and cooperating therewith to form chambers at the ends of said cage, and lampholders located in said chambers and sustained by said end closures and having lamp socket portions opening into said cage and adapted to support said lamp therein, said cover member constituting a reflector and eye shade and having spring fastener members adapted for snap engagement with said trim strips, and means secured to said fixture for supporting it on its side and for preventing it from rolling sidewise in such supported position.

7. A portable electric lighting fixture comprising a light transmitting tube with closed chambers at the ends thereof, lampholders located

- in said chambers and having sockets opening into the ends of said tube for supporting a tubular lamp therein, said tube having a longitudinal access opening in the side thereof through which said lamp may be inserted and removed sidewise, a member secured to said tube for covering the opening therein, said member constituting a reflector and eye shade, and means secured to said fixture for supporting it on its side and for preventing it from rolling sidewise in such supported position, said means comprising runners extending longitudinally of said fixture and supporting the same for rotation about the longitudinal axis of said tube.
8. A portable electric lighting fixture comprising a lamp enclosing cage including a wire screen tube having a longitudinal access opening in the side thereof through which a tubular lamp may be inserted and removed sidewise, trim strips secured to said screen and defining the edges of said opening, closures for the ends of said tube, a cover member for said opening, cup-shaped caps secured to said end closures and cooperating therewith to form chambers at the ends of said cage, and lampholders located in said chambers and sustained by said end closures and having lamp socket portions opening into said cage and adapted to support said lamp therein, said cover member constituting a reflector and eye shade and having spring fastener members adapted for snap engagement with said trim strips, and means secured to said fixture for supporting it on its side and for preventing it from rolling sidewise in such supported position, said means comprising a bail member connected to one end of said fixture to swing alongside thereof to support the same in a reclining position and against sidewise rolling in such position.

DAVID J. BILLER.
